CASSETTE TRANSPORT

Orville W. Larson, Elmhurst, Ill., assignor to Ampex Corporation, Redwood City, Calif., a corporation of California

Filed Aug. 18, 1969, Ser. No. 18,725

Term of patent 14 years

Int. Cl. D14—01

U.S. Cl. D26—14

FIG. 1

FIG. 2

FIG. 1 is a front, top and left side perspective view of a cassette transport showing my new design, the right side and back being mirror images of the left side and front, respectively, and the bottom being conventionally plain; and

FIG. 2 is a plan view of the transport with the transparent dust cover removed.

I claim:

The ornamental design for a cassette transport, substantially as shown and described.
